UNITED STATES PATENT OFFICE.

ALEXANDER D. ROSE, OF CHICAGO, ILLINOIS, ASSIGNOR TO JAS. P. MARSH & COMPANY, OF CHICAGO, ILLINOIS, A CORPORATION OF ILLINOIS.

DESIGN FOR A THERMOMETER.

Application filed June 15, 1928. Serial No. 27,144. Term of patent 14 years.

To all whom it may concern:

Be it known that I, ALEXANDER D. ROSE, a citizen of the United States, residing at Chicago, in the county of Cook and State of Illinois, have invented a new, original, and ornamental Design for a Thermometer, of which the following is a specification, reference being had to the accompanying drawing, forming a part thereof.

In the drawing,

Fig. 1 is a front elevation of a thermometer, showing my new design;

Fig. 2 is a side elevation of the thermometer; and

Fig. 3 is a section on line 3—3 of Fig. 1.

I claim:

The ornamental design for a thermometer, as shown.

ALEXANDER D. ROSE.
